FEEDER MECHANISM FOR CIRCULAR
KNITTING MACHINES

Roland Peberdy, Leicester, England, assignor to
The Bentley Engineering Company Limited,
Leicester, England.

Application June 11, 1947, Serial No. 753,981
In Great Britain June 20, 1946

5 Claims. (Cl. 66—131)

1

This invention concerns feeder mechanism for circular knitting machines, especially circular knitting machines of the opposed needle cylinder type wherein needles are capable of transfer from one needle cylinder to the other. Of such machines the superimposed needle cylinder machine is the sole embodiment at present in commercial use. In such machines it is generally necessary to locate the thread feeders outside the needle circle, and this involves difficulties when it is desired so to arrange matters that a thread feeder may be moved into and out of operation or thread feeders may be interchanged. These difficulties are pronounced in the case of the splicing feeder of a machine of the aforesaid type which is constructed and arranged for the manufacture of seamless hose and the like, said splicing feeder remaining in feeding position for a portion only of each course.

It will be understood that when in feeding position the splicing feeder eye should be located as close as practicable to the needles, in the somewhat restricted space between the feeder for the main or ground yarn and the location at which the needle latches close. The path of movement of the feeder eye into and out of feeding position must be such that it misses the closing latches, and its outward path must carry the running yarn into a trapper and cutter which should be located as close as possible to the needle circle so that it cuts the splicing thread as close as possible to the last needle that has knitted it so as to avoid the formation of free ends of undue length at one edge of the spliced area.

It is further desirable that the two alternative positions of the feeder eye, in relation to the trapper and cutter and to the knitting point, shall be such that when the length of yarn extending from the introduced feeder eye to the trapper and cutter is taken by the needles and is released by the trapper, substantially the whole of said length shall be knitted up.

These requirements are difficult to meet.

In seamless hose and half hose machines of the type specified, two constructions of splicing feeder mechanism have been employed. In one, the feeder arm swings about an axis parallel to that of the needle cylinders. Difficulties are experienced in designing satisfactory mechanism of this construction. On the one hand, if matters are so arranged that the length of splicing thread extending from the withdrawn feeder eye to the trapper and cutter is not to be greater than that extending between the two said parts when the

2

eye reaches the feeding position, the path of travel of an eye to clear the closing latches results in a feeding position which is comparatively widely spaced to the outside of the needle circle. On the other hand, if the axis of movement of the feeder is so disposed that the arcuate path of movement of the eye to clear the closing latches brings the eye close to the needle circle the difficulty arises that when the eye reaches feeding position it is then more close to the trapper than it is when in its non-feeding position so that, at the moment of introduction, the length of thread that extends from the eye to the trapper is not taut but is slack and bowed and is therefore not introduced to the needles with certainty at a predetermined needle but in a haphazard manner which results in a "ragged" edge to the spliced area. In another construction the feeder is substantially L-shaped and lies in a plane normal to the cylinder axis, one arm of the L being tangential to a circle concentric with said axis and the other arm protruding therefrom inwards towards the needle circle. In this second construction, to introduce the feeder the latter is moved lengthwise of the first mentioned arm and then the whole feeder is rocked towards the needle circle. This mechanism has the disadvantage that the moving parts are comparatively heavy with the result that its useful life leaves something to be desired.

A specific object of the present invention is to provide splicing mechanism which overcomes the aforesaid difficulties, but it will be appreciated that the mechanism provided by the present invention is not restricted in its utility to machines of the opposed needle cylinders type.

With this and other objects in view the present invention provides in or for a circular knitting machine, feeder mechanism comprising a feeder arm having a feeder eye at its extremity, and means mounting said arm for movement about a plurality of axes all substantially parallel with the axis of the needle circle and for movement of the feeder eye in a thread-withdrawing path, the first portion of which is substantially radially away from the needle circle and the subsequent portion of which is substantially circumferentially of the circle.

The construction specified in the preceding paragraph has the advantage that the path of the feeder eye may be such that it clears the closing latches in movement into and out of a feeding position which is close to the needle circle and which is close also to the ground feeder and to the location at which the latches close,

while simultaneously ensuring that the length of thread extending from the eye to the trapper at the moment of introduction of the thread to the needles is not less than that extending from the withdrawn eye to the trapper at the moment of trapping. Furthermore, the trapper and cutter may be located close to the needle circle and the feeder eye may, in its inoperative position, be located close to the trapper and cutter.

The foregoing and other features of the invention set out in the appended claims, are incorporated in the construction which will now be described, as an example of the application thereof to the splicing feeder of a seamless hose or half-hose machine of the superimposed needle cylinder type, with reference to the accompanying drawings in which:

Figure 1 is a side elevation showing the relevant parts of the knitting machine and of the splicing feeder mechanism, and

Figure 2 is a plan thereof.

In Figure 1, the latch needles are shown at 1, while in Figure 2 the needle circle is indicated at 1' and the position at which the latches close is indicated by the line L. C. The splicing feeder arm 2 is of elongated rod form and, in its operative position shown in Fig. 2 in full lines, occupies a substantially radial attitude. Its outer end is slidably received in a guide block 3 which is itself pivotally mounted on a bracket 4 for movement about a vertical axis (i. e. an axis which is parallel to the axis of the needle cylinder). Slightly inwards of this pivot the arm 2 is fixed to a pivot block 5, also having a vertical axis, on a horizontal swinging arm 6 which is itself movable about a vertical axis at 15, and which when the feeder is in the feeding position, extends substantially at right angles thereto. Therefore, assuming the feeder eye 7 to be in the feeding position, in pivotal movement of the swinging arm 6 away from the needle cylinders the feeder 2 is first caused to slide through the guide block 3 (accompanied by but little pivotal movement of the latter) so that the eye 7 moves substantially radially away from the needle circle 1' with little movement circumferentially of said circle (thus permitting the eye to travel outwards until it is located at a radius greater than that of the closing latches), then, as the swinging movement of the arm 6 progresses and the angle included between the arm and the outer end of the feeder increases the sliding movement of the feeder in the guide block 3 is reduced and its pivotal movement increases, with the result that the feeder eye 7 moves circumferentially of the needle circle. This movement takes the eye along the path indicated by the dotted line F. P. in Figure 2, past the closing latches to a position (also shown in dotted lines in Figure 2) adjacent to a trapper and cutter 8 which is itself located close to the needle circle 1'.

The swinging arm 6 is movable between adjustable stops 9, movement in one direction (preferably that which carries the feeder into operative position) being imparted to it through a push rod 10 and movement in the other direction being imparted to it by a tension spring 11. This push rod 10 is engaged with an adjustable tappet 12 at the upper end of an operating lever 13 to which the spring 11 is also connected. This lever 13 is of bell crank form, its second arm being bifurcated so that the two fork arms 13a, 13b engage respectively with each of two cams 16, 17 of a rotary timing device 14 whereby positive movement of the feeder into and out of

operation is secured and the feeder is always under positive control. In order to avoid fitting operations on the cams each cam consists of two parts or discs 16a, 16b, or 17a, 17b that are adjustable circumferentially. These parts consist of a nose on one disc which serves to shift the associated fork arm and a filling up cam, on another disc, which is intended to maintain engagement with said fork arm until that phase in the cam rotation at which the nose of the other cam operates to shift the fork arm. Additionally, the two fork arms 13a, 13b are frictionally connected to one another and to the operating lever, the required pressure being applied by compression spring 18 and adjusting nut 19 acting against a thrust collar 20 on the lever spindle 21.

Any suitable mechanism is provided for imparting continuous rotation to these cams 16, 17 through spindle 22.

It will be understood that as the feeder eye 7 is withdrawn, the thread T extends from it in a direction tangentially of the needle circle 1' and this movement, together with the anti-clockwise rotation of the needle cylinder or cylinders, eventually carries that length of thread, that extends from the eye to the last needle to knit it, into the trapper and cutter 8. In the reverse movement into feeding position, the eye moves in at the leading side of the closing latches (i. e. at a position in advance of the line L. C.) so that the thread T extending from the eye to the trapper and cutter is enclosed within the needle hooks by the latches. It will further be appreciated from Fig. 2 that the trapper and cutter may be located very close to the needle circle in a position wherein the distance between, and the length of thread extending between the eye and the trapper and cutter at the moment of introduction is not less than the distance between, and the length of thread extending between the eye and the trapper and cutter at the moment of trapping. The ground feeder (not shown) may be located closely in advance of the operative position of the splicing feeder.

Having now particularly described and ascertained the nature of my said invention and in what manner the same is to be performed, I declare that what I claim is:

1. In a circular knitting machine, feeder mechanism comprising a feeder arm having its feeding end disposed adjacent to the needle circle, a pivotal mounting on which the arm is movable about an axis substantially parallel to the axis of the needle circle, a lever on which the mounting is itself carried and which is pivotally movable about an axis substantially parallel with the two previously mentioned axes, a guide on which the arm is slidably at a location more remote from the needle circle than is the pivotal mounting, which guide is also movable about an axis substantially parallel with the three axes aforesaid, and means for rocking the lever to and fro.

2. In or for a circular knitting machine, feeder mechanism comprising a feeder arm having a feeding eye at its extremity, and means mounting said arm for movement about a plurality of axes all substantially parallel with the axis of the needle circle and for movement of the feeder eye in a thread-withdrawing path, the first portion of which is substantially radially away from the needle circle and the subsequent portion of which is substantially circumferentially of the circle.

3. Feeder mechanism according to claim 2, for a machine having a rotary needle cylinder, where-

in the feeding end of the feeder moves in the direction of rotation into its non-feeding position.

4. In a circular knitting machine, feeder mechanism comprising a feeder arm, having a feeding eye at its end for feeding a yarn to the needles, a pivotal guide on which the arm is slidable in the direction of its length towards and away from the needle circle and is pivotally movable about an axis substantially parallel to the axis of the needle circle, a pivotal mounting for the arm at 10 a location spaced from the axis of the needle circle and from the pivotal guide; and mechanism for shifting said pivotal mounting, about an axis which is substantially parallel to the axis of the needle circle and to the axis of the pivotal guide, and for simultaneously sliding the arm on the pivotal guide in movement of the feeding eye between feeding and non-feeding positions.

5. A machine according to claim 2, having a trapper and cutter for receiving and cutting the 20

thread extending from the withdrawn feeder to the last active needle which trapper and cutter is located very close to the needle circle in a position wherein the distance between the eye and the trapper at the moment of introduction of the thread to the needles is not less than the distance between the eye and the trapper at the moment of trapping.
